HOSPITALIZATION AND POSTURE BED

Charles Drexler and Ralph H. Morgan, Indianapolis, Ind., assignors to Robert R. Freund, Mount Carmel, Ill.

Application March 13, 1940, Serial No. 323,677

9 Claims. (Cl. 5—66)

This invention relates to a posture bed.

This application is a continuation-in-part of the copending application, "Hospitalization Bed", Serial No. 152,718, filed July 9, 1937, now matured into Patent No. 2,261,980 issued Nov. 11, 1941, and relates more particularly to the subject matter of original claims 5 and 17, thereof, and the disclosure therein is made a part hereof.

The specific control per se including manual and power operable means thereof as well as that more or less diagrammatically illustrated herein, is the subject of a copending divisional and continuation-in-part, copending application, entitled, "Power and control for articulated beds," filed March 13, 1940, and bearing Serial No. 323,676, and relates to original claims 6 to 12 and 18 to 21 of application Serial No. 152,718.

The present invention also is a continuation-in-part application relative to the articulated bed, bed pan support and a plug combination now claimed in copending application Serial No. 152,718.

The present invention also is an improvement upon the articulated bed structure embodying basically the articulated bed, bed pan support and plug combination and manual and electric power and controls therefor initially disclosed in the Robert R. Freund, "Posture bed structure," application Serial No. 151,272, filed December 11, 1936, and the instant application is copending with the substituted application similarly entitled and filed March 29, 1939, and bearing Serial No. 264,766 for said Freund application.

In view of the copending application Serial No. 323,676, filed March 13, 1940, describing and claiming the power and control means of the bed herein disclosed, the instant application is directed more particularly to the improvements in the articulated bed, bed pan support and plug combination over that disclosed in the aforesaid duplicate Freund applications.

Since the introductory portions of applications, Serial No. 151,272, No. 264,766 and No. 152,718 set forth quite fully the objects and features of the invention basically common to the instant disclosure said objects may be briefly outlined as follows:

The chief object is to provide a bed of articulated character, whereby the same may have its several parts moved into various positions necessitated by the patient's particular condition.

Another object of the invention disclosed herein is to provide a mutually coacting combination bed pan and mattress plug arrangement, wherefore either may be associated with an aperture in

the bed spring and mattress for the specific purpose desired.

Another object of the present invention is to improve the inventions basically disclosed in the aforesaid Freund and Drexler-Morgan applications.

The chief feature of the invention consists in embodying in a bed structure of articulated character the several mechanisms hereinafter more fully set forth, whereby the bed sections and portions associated therewith may be adjusted, maintained, operated and/or utilized, as necessity or convenience may require.

The advantages of an articulated bed structure embodying the basic characteristics of the present invention and those of the copending applications referred to are common and well known and require no repetition.

Objects and features other than the foregoing and specific to the instant disclosure will be pointed out more fully hereinafter.

The full nature of the invention will be understood from the accompanying drawings and the following description and claims.

In the drawings, Fig. 1 is a rear elevational view of a bed structure embodying the invention, the back section of the bed frame being shown elevated and the movable foot and knee sections and the stationary section being omitted since in this view the same are concealed by the back section, the pan support being shown in the lowered position and the plug section mechanism being shown in the elevated position.

Fig. 1—A is a plan view of the knee section control.

Fig. 2 is a vertical sectional view through the invention, the same being taken approximately in the plane of line 2—2 on Fig. 1 and in the direction of the arrows, the foot and knee sections 40 of the bed being illustrated in lowered and horizontal positions, respectively.

Fig. 3 is a similar view of a portion of the mechanism illustrated in Fig. 2 but with the back or head section of the bed in horizontal position and the foot and knee sections reversely positioned in tilted positions although generally horizontally directed, this being the knee strain removing position, the heavy broken horizontal line to the left indicating the position of the foot section when elevated to substantially horizontal position when the circulation of the patient requires that the legs be elevated relative to the head and torso.

Fig. 4 is a sectional view of the bed pan support and plug mechanism corresponding to the

position of said parts, as shown in Fig. 1 and same is taken approximately on line 4—4 of Fig. 1 and in the direction of the arrows.

Fig. 5 is a similar view of the same parts, the pan support and plug positions being reversed.

Fig. 6 is a transverse sectional view taken on line 6—6 of Fig. 5 and in the direction of the arrows when the pan section is below the section line 6—6.

Fig. 7 is a similar view taken on line 7—7 of Fig. 4 and in the direction of the arrows when the plug support is below the section line 7—7.

Figs. 6 and 7 are representative of the relative positions of the bed pan and plug support members in the respective channels guiding same.

In the drawings—see Fig. 1—10 indicates one frame member and 11 the opposite member. Each is approximately rectangular in outline, see Fig. 2, and at each lower corner terminates in a socket 12 with which is associated a thumbscrew 13 or the like for clamping in adjusted position, the pintle portion of an arm 14 that extends angularly thereof and terminates at its lower free end in a socket 15 detachably or otherwise suitably mounting a swivelling caster 16.

Two upper tie rods 17 and a median lower rod 18 secure these frame members together in spaced relation and constitute the pedestal and base formation. Swivelling the arms 14 so same underlie or are within this frame outline positions these elements so that the bed may readily be moved through doorways, et cetera, and without dismantling when the articulated sections are positioned substantially as shown in Fig. 2.

The articulated bed frame includes a head or back U-shaped portion or section 19 pivotally mounted within the frame and near the upper right hand end thereof as at 20, see Fig. 2. Also pivotally mounted within the frame and closer to the other or forward end than the last mentioned or rearward end and as at 21 are the connected portions 22. The frame has intermediate portions 23 which constitute the intermediate stationary or seat section, connected portions 22 constituting the knee section.

A reversely positioned U-shaped member 24 has its arm free ends similarly pivotally mounted as at 25 on the knee section. These pivots are movable being at the free end of knee section 22. As shown in Figs. 2 and 3, the back or head section 19 may be positioned upright or horizontally, or in any intermediate position as desired. Similarly, knee section 22 may be tilted upwardly from stationary section 23, be in alignment therewith or be slightly tilted downwardly therefrom or be positioned in any intermediate position, as desired.

Also foot section 24 may be dropped as illustrated in Fig. 2 or tilted downwardly from above the horizontal plane of the bed proper as illustrated in Fig. 3 or may be horizontally positioned at that elevation, see the heavy broken line in Fig. 3, or may be horizontally aligned with all sections in what is considered the normal bed plane.

Each section includes flexible metal straps 26 connected at opposite ends by helicals 27 to the adjacent frame portion except that the stationary section also includes a central opening not shown herein.

The articulated bed structure supports an articulated mattress, the articulations occurring therein adjacent and registering with pivots 28 and 29. It may also be articulated adjacent pivots 21, if desired. It includes an opening there-

through (not shown) registering with the stationary seat section central opening described but not shown. A mattress plug 28—see Figs. 4 and 5—is arranged to close this opening. The illustration of the aforesaid mattress is intentionally omitted from the drawings for clearness.

Reference now will be had more especially to the right hand portion of Fig. 1 and the central portion of Fig. 2. Therein, member 11 is shown supporting a housing 29 having cover 29a upon which is mounted the manual selector device 30. Through the lower cover portion 29b extends shaft 31 which mounts hand crank 32. This is the common manual power.

15 A reversible motor 33 is suitably supported by member 11 and within the frame structure. Thereabove in aligned relation, see Figs. 1 and 1A, are the bearings 34, 35, 36 and 37 extending inwardly from member 11 and projecting therefrom 20 are the shafts 38, 39, 40 and 41, respectively. These shafts—see Figs. 1, 2 and 3—are substantially in vertical alignment and accordingly, in superposed relation.

Shaft 38 is the plug and bed pan support actuator shaft. Shaft 39 is the combination back and knee section actuating shaft. Shaft 40 is the foot section actuating shaft and shaft 41 is the independent knee actuating shaft.

25 The connections between these shafts and the 30 motor or crank, and the manually remote or manually direct operable controls associated therewith, the interlocking safety controls associated therewith, the interlocking safety devices, overrunning limit switches, clutches, controls 35 therefore, etc., are intentionally omitted from the drawings and description of this invention, since the same are fully illustrated described and claimed in the second section of the copending application, entitled, "Power and control for articulated beds," hereinbefore mentioned and to which reference is here made for a complete understanding of the present invention.

30 The back section 19 adjacent its pivotal support 20 includes at opposite sides lateral extensions 42 which are connected by portion 43, see Figs. 2 and 3. Portion 43 is relieved at 44, see Fig. 1, to facilitate pan removal when the back section 19 is horizontal and for pan support and plug clearance.

50 Adjacent member 11 is integral with the junction of portions 42 and 43, is an angular arm 45, the angularity therein occurring at 46 to clear the adjacent tie rod 17, see Fig. 2.

The lower end of the singular arm 45 is pivotally connected at 47 to a link 48 in turn pivotally connected at 49 to the power arm 50 rigid with the second lowest shaft—see Fig. 2. Each of the two back section connected arm portions 42 mounts a roller 51 that rides in an elongated

60 slot 52 in a lever arm 53 pivotally mounted upon the exposed portion of uppermost shaft 41 at one side of the frame and upon a suitable pivot in axial alignment therewith on the opposite side of the frame. Each lever arm 53 at its forward end 65 rotatably supports a shaft 61 which in effect is a floating pivot because shaft 61 is independent of the frame. Both levers 53 are thus connected at their forward ends by shaft 61 and at their rearward ends by arms 42 and the back and head section.

70 The slot 52 for the major portion of its length is arcuate and substantially concentric with the axis of pivot 20, the hinge axis of the back section. At the forward end of each slot 52 is an offset portion 52a which has a cam effect. When

the back section is initially tilted from the horizontal position upwardly or finally lowered to horizontal position, these offset portions 52a of slots 52, through arms 42 and rollers 51 tilt lever arms 53 clockwise and counterclockwise, respectively, see Fig. 2, which means that shaft 61 is shifted substantially vertically accordingly; hence, shaft 61 is a floating pivot for the two arms 59. These arms, see Fig. 1—A are positioned within arms 53 but may be positioned between the arms and the adjacent frame members in which event they would be on the ends of shaft 61 instead of arms 53, as shown.

Each arm 59 terminates in a roller 53 which rides in an elongated slot 51 in a depending flange 56 at the longitudinal side of the knee section 22. Accordingly, as the back section is initially raised, the knee section 22 automatically will be raised therewith to the extent obtained by the shifting of pivot shaft 61 through arms 42 and rollers 51 while associated with portions 52a of slots 52 in the levers 53. Further back section elevation has no corresponding knee section movement. Conversely, when the back section is finally lowered to horizontal position, the knee section, if tiltably elevated the proper amount automatically will be lowered to horizontal position by the lowering of pivot shaft 61.

Also rigid with shaft 61 for rotation therewith is the arm 60 adjacent member 11 and pivotally connected at 55 to link 62 pivoted in turn at 63 to arm 64 rigid with the uppermost shaft 41. By reason of the pin (roller) and slot 51—58 connections in flanges 56 the knee section can be raised and lowered independently of back movement or simultaneously therewith (under electric motor power only) or by back movement only as previously set forth.

Along the underface of each side or arm portion of the U-shaped foot section 24 is a guide or track 66. Adjacent each is a roller 67 carried by the free end of lever 68 pivoted at 69 upon the adjacent frame member. The numeral 69 indicates a shaft that is rotatably supported in confronting aligned bearings in frame members 10 and 11. Not only are levers 68 rigid with said shaft 69 but also lever 70 is rigid therewith, which lever is pivotally connected at 71 to a link 72 in turn pivotally connected at 73 to lever arm 74 carried by power shaft 40. Rods 75 and 75a constitute tie rods between side arms 24 and levers 68, respectively.

Reference now will be had to all of the figures of the drawings since therein is disclosed the bed pan support and the plug mechanism and the inter-action or correlated movement therebetween and the power for operating the same. As previously set forth, Fig. 1 shows the bed pan support in the lowered position, thus corresponding to the position of the structure, as illustrated in Fig. 4, whereas the reverse arrangement or positioning is illustrated in Fig. 5.

By referring to Figs. 1, 4 and 5, it will be observed that the lower central bar 18 which extends from one frame member 10 to the opposite frame member 11 has pinned thereto or otherwise suitably secured thereto, U-shaped or slotted guide members 76, the slots therein being upwardly directed and indicated by the numeral 77. A pin 78 including a roller rides in said slot and to it is connected a pair of elongated springs 79 which are upwardly and outwardly directed, that is, fore and aft, and have their upper ends anchored as at 80 to the two transverse rods 17

which constitute frame member connecting means.

5 A substantially rectangular frame 81 at each side substantially parallel to the frame members 10 and 11 is provided with a depending portion 82. The rectangular member 81 is provided with a central opening 83 therein and this frame member 81 is yieldingly connected, as previously described, to the stationary section of the bed structure through the mattress supporting means. In order that this structure shall not constitute an objectionable abutment for a patient of considerable weight, the aforesaid frame structure 81—82 is floatingly supported, as it were, because the two depending parallel portions 82 mount at their lower ends the outwardly directed pins 78 that ride in the adjacent slots 77 of the upright guide members 76. As the weight comes on the frame 81, the four springs which are arranged in pairs, each pair being arranged in V-shaped relation, elongate and thus cushion or compensate for the excessive weight of the patient. This auxiliary frame, therefore, is floatingly associated with the main frame structure in the manner described.

25 The plug and bed pan support mechanism and operating means therefor is all carried by or associated with this floating auxiliary frame, previously described. The depending members 82 near the lower end are provided with aligned 30 bearings 84, the right hand one—see Fig. 1—having an opening entirely therethrough so as to receive and rotatably support the shaft 85, the free end 86 of which extends beyond the 35 right hand frame member 82. A universal coupling 87 is connected to shaft 85 at 88 and at 89 is connected to the outer end of the shaft 38. This is the power supply to the mechanism.

40 A pair of walking beams 90 is counted in spaced relation upon said shaft 85 and suitably secured thereto. The forward ends of the walking beams herein illustrated as the upper end in Fig. 1 and designated by the numeral 91, are pivotally connected as at 92 to the ends of arms 93 pivotally connected as at 94 to a shaft bearing the same designation and which is rotatably supported in bearings connected by the side webs 95 of the plug support base 96 to which is suitably secured the mattress plug 28 previously referred to.

45 50 Rotatably and medianly supported on the shaft 85 is an angular housing 97 which has an elongated bore 98 extending therethrough and offset or non-intersectingly positioned with reference to the pivotal mounting of said housing. Slidingly supported therein is a guide rod 99 which mounts a stop collar 100 between the plug support 96 and the housing 97.

55 60 A pair of coil springs 101 is connected at one end to the shaft 94 and is connected at their opposite ends to anchorages 102 carried by the beams 90 adjacent the ends 91 thereof, but sufficiently spaced therefrom so as to secure the desired operation therefrom, the springs and arms 93 forming a triangle with the included portion of the walking beam therebetween, as shown in Fig. 5.

65 70 In alignment with shaft 94 or as extensions thereof at opposite ends and immediately adjacent the two depending portions 82 of the auxiliary frame and beyond the walking beams, are guide elements 103 which ride in the slots or grooves 104 which confront each other and are formed upon the inside adjacent faces of the 75 depending members 82.

The bed pan support includes an open work peripheral type bed pan conforming frame 105 which at opposite sides is provided with three pairs of bosses 106, 107 and 108, the same constituting supports for mechanism herein after described. A rod 109 is pivotally connected at one end to the bearing 106 and is telescopically associated with the cylinder 110 which in turn is pivotally mounted at 111 upon a fixed pivot on the depending frame member 82. The opposed bearing 108 on the same side of the pan support member 105 is carried by the web 112 and pivotally connected at the bearing is a rod 113 for telescopic connection with the cylinder 114 in turn pivoted at 115 in a fixed bearing on the depending frame member 82, it being observed the bearing 111 is positioned—to the left in Fig. 5—and above the center of the member 82, including the shaft 85 as distinguished from the bearing 115 which is positioned to the right in Fig. 5 and below and rearwardly of the aforesaid.

Intermediate the bearings 106 and 108 is the bearing 107 previously mentioned and therein is mounted member 116 which at its outer ends mounts stop and vertical aligning members 117. The vertical aligning members 117 are adapted to first engage the wall forming portion of the groove 119 and then to seat in said groove. The common wall 120 thus engaged forms adjacent sides of the adjacent aligning grooves or ways 104 and 119.

Pivots connected to the rod 116 and between the depending webs 112 are links 121. Stop collars 122 maintain these links in predetermined parallelism and spaced relation. The other ends of these links are pivotally connected as at 123 to the other ends 124 of the walking beams before mentioned. Ends 124 are bifurcated for such purpose and in that respect are similar to the bifurcated ends 91 at the opposite ends of the walking beams.

The foregoing in brief constitutes a description of the bed pan support and plug support mechanism and the operative mechanism necessary therefor.

When the parts are positioned as shown in Figs. 4 and 1, the bed pan support is maintained normally horizontal and the plug is maintained normally horizontal, the latter being in aligned relation and in registration with the aperture 83 of the auxiliary frame structure including the frame arrangement 81, the base 96 supporting the plug 28 then being in substantial horizontal alignment, as shown in Fig. 4, with the stationary section of the bed.

When the shaft 38—85 is rotated and to the limit of its movement, the parts move from the position shown in Fig. 4 to the position shown in Fig. 5. In this position the plug is tilted and is now lowermost whereas the bed pan support is still horizontally positioned but is in elevated relation and is seated within the peripheral portion of the auxiliary frame 81 which as has been previously described, is of floating character.

Inasmuch as all the power mechanism and all the support mechanism for the plug and bed pan support are carried by and movable with the auxiliary or floating frame structure, no relative movement occurs therebetween by reason of the imposition or variation in any load. With the parts positioned as shown in Fig. 4, it will be noted the plug is fully elevated, the walking beams are extended almost upright and slightly forwardly and the adjacent springs are fully extended and the guide rod is also fully extended

relative to the intermediate housing 97 carried by the shaft 85.

When the mechanism, that is, shaft 38—85 is reversely operated to lower the plug and elevate the bed pan support, the initial movements are as follows: The walking beams and links connecting the same to the plug support collapse towards each other, the central guide member extends into the housing 97 for telescopic movement and the plug 28 and its supporting platform drop vertically from the opening in the mattress and the opening in the auxiliary frame. At the same time the bed pan moves upwardly and due to the two pairs of parallel rod and cylinder constructions, the same constituting a parallelogram construction, said bed pan support moves upwardly and non-interferingly until the plug has lowered to a position below the lower edge of the rim of the peripheral auxiliary frame. Continued operation then tilts the plug forwardly and downwardly and continues to move the bed pan support upwardly as well as forwardly until the bed pan is positioned a slight distance below the opening in the auxiliary frame while the rearward upper edge of the plug is in approximately horizontal alignment with said pan support. At this position the two guide members previously described, engage the intermediate guide and way or groove forming portion and further forward movement of the bed pan is prevented.

It will be observed that at this point in the movement, the central guide member has very nearly fully telescoped into the tubular housing 97. Continued rotation of the power shaft through the walking beams and by reason of the guide constraint imposed, causes the bed pan structure movement to continue as elevation only, all the while the bed pan being maintained in the horizontal position until the walking beams are substantially vertical and in alignment with the links connected thereto and to the bed pan support. At this position—Fig. 5—with the bed pan support elevated, the bed pan lies below the upper plane of the mattress and also below the upper plane of the auxiliary frame and the plug structure is positioned in its lowermost position, as shown in Fig. 5, where it just clears the floor or supporting surface. Reverse operation of the power shaft secures a reverse movement to the position shown in Fig. 4. Throughout the movement of raising and lowering the bed pan structure, the bed pan structure support element is always maintained horizontally.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In an articulated bed structure, the combination with a plurality or sequentially and hingedly connected sections, one end section being tilttable upwardly and the other end section being tilttable downwardly from horizontally aligned relation, and a frame of materially less length than that of the sections when horizontally aligned and of a width substantially that of section width, of elongated angularly offset downwardly directed leg means pivotally supported at each of the frame corners on vertical axes and mov-

able into collapsed relation beneath the frame for bodily movement of the bed structure through a door opening without bed dismantling and into extended relation relative to the frame for large area support of the bed structure outline when in use as a bed, and castor wheel means swivably supported by the lower end of each leg means for movement upon an axis transverse to the wheel axis and offset from but parallel to the leg means pivotal axis.

2. The combination with a frame arrangement, a seat section rigid therewith, a back and head section pivotally mounted at one end of the seat section, a knee section similarly mounted at the opposite end of the seat section, a foot section pivotally connected to the opposite end of the knee section, said sections when horizontally aligned forming a bed arrangement, of a pair of pivotally mounted levers and having their free ends engageable with the side portions of the 20 foot section for support and independent adjustment thereof, lever means having similar engagement with the side portions of the knee section, for support and independent adjustment thereof, movement of the lever means for knee section movement resulting in corresponding movement of the foot section independently of said foot section levers, lever means for tilting the head section, means for tilting said levers, other means for tilting the first mentioned lever means, still other means for tilting the second mentioned lever means, each of said means being independent of each other and independently adjusting the immediate connected section, and means operatively connecting the head section and the knee section adjusting lever means for predetermined knee and foot section adjustment with and by head section adjustment.

3. In an articulated bed structure, the combination with a plurality of sequentially and hingedly connected mattress supporting spring sections, and an open-work, section supporting frame of lesser length than the sections when extended and of a width substantially that of the sections, of means for individually moving a plurality of said sections, each means including an arm within and at each side of the frame and section connected, a member extending from arm to arm for simultaneous arm movement, said a third arm rigid with the member and adjacent one side of the frame, a plurality of superposed shafts extending through the last mentioned side of the frame, an arm on the frame included end of each shaft and a link for each fourth mentioned arm connecting the last mentioned and third mentioned arms for shaft movement of the section, the frame exposed ends of the shafts being arranged for rotational power application, the link connected arms and the link therebetween constituting a parallel motion arrangement for section associated member connected arms operation.

4. A structure as defined by claim 3, characterized by the addition of a single motor carried by the lower portion of the frame and with- 65

in the outline of the same and arranged for operation of the frame exposed ends of the shafts, and cover means for the latter and removably secured to the frame.

5. A structure as defined by claim 2, characterized by the axis of the knee section lever means being shiftable automatically with and by the head section initial movement from bed forming position and for corresponding knee section movement and independent of the tilting means for the knee section lever means.

6. The combination with a frame arrangement, a seat section rigid therewith, a combined back and head section pivotally mounted at one end of the seat section, a knee section similarly mounted at the opposite end of the seat section and capable of movement above the plane of the seat section, a foot section pivotally connected at one end directly to the knee section, the sections being sequentially connected and when horizontally aligned forming a bed arrangement, of independent means for each section except the seat section for independently moving the pivoted sections, the foot section independent moving means having slidable bearing connection with the foot section permitting foot section movement in accordance with said foot section independent moving means as well as with movement of the knee section, and means operatively connecting the head and knee sections together for simultaneous knee section movement in accordance with initial, elevational movement of the head section and vice versa, and foot section movement in accordance with the last mentioned knee section movement, the knee section and its independent moving means having slidable bearing connection.

7. A structure as defined by claim 6, characterized by the last mentioned knee section slideable connection including an elongated slot substantially parallel to the plane of the knee section, and movable means having a portion in the slot and slideable therein for the purpose described.

8. A structure as defined by claim 6, characterized by the means operatively connecting together the head and knee sections including a member having an elongated slot, and means having a portion slideable therein for the purpose described.

9. A structure as defined by claim 6, characterized by the last mentioned knee section slideable connection including an elongated slot substantially parallel to the plane of the knee section, movable means having a portion in the slot and slideable therein for the purpose described, the means operatively connecting together the head and knee sections including a member having an elongated slot, and means having a portion slideable therein for the purpose described, the aforesaid slotted connections being sequentially arranged.

CHARLES DREXLER.
RALPH H. MORGAN.
